SOAP DISPENSER

Howard A. Mullett, Milwaukee, Wis., assignor
to Bradley Washfountain Company, Milwaukee, Wis., a corporation of Wisconsin

Application March 9, 1936, Serial No. 67,804

4 Claims. (Cl. 221—94)

The invention relates to devices for dispensing powdered, granular, or other types of soap in finely divided form.

The main object of the invention is to provide a dispensing mechanism which forms the outlet of a soap receptacle and which permits a certain predetermined amount of soap to be withdrawn from the receptacle and insures its efficient delivery to the user. More particularly according to the present invention the dispensing and measuring mechanism includes two parts which are movable with and relative to each other and form an annular pocket in which the soap is received and from which it is forcibly discharged after its withdrawal from the soap receptacle.

A further object of the invention is to provide a soap dispensing device of the character above described in which the amount of soap dispensed may be regulated by varying the stroke of one of the dispensing members.

20 A further object of the invention is to provide a dispensing mechanism associated with a receptacle for the soap being dispensed and which may be readily removed therefrom as a unit.

25 The invention further consists in the several features hereinafter set forth and more particularly defined by claims at the conclusion hereof.

In the drawing:

Fig. 1 is a vertical sectional view through a 30 device embodying the invention showing it in discharged position;

Fig. 2 is a view similar to Fig. 1 showing the device in charging position;

Fig. 3 is a detail sectional view taken on the line 3—3 of Fig. 1.

35 In the drawing, the numeral 5 designates a portion of a receptacle, tank, or reservoir containing the soap to be dispensed and having a threaded bottom opening 6 in which the threaded portion 7 of a base member 8 is detachably mounted.

40 The metal base member 8 has a depending discharge chute portion 10 which, intermediate its ends, connects by radially disposed arms 11 with an annulus 12. Bolts 13 are also mounted in said member 8 and with the aid of spacer sleeves 14 support a guide and spring housing member 15 above said base and in line with a bore 16 therein.

45 A hollow plunger 17 has a tubular portion 18 working in the bore 16 and the corresponding bore 19 of the member 15 and has a tubular portion 20 of less diameter which passes through the central opening of the annulus 12 and also through a tubular sleeve or dispensing part 21 whose outer diameter is the same as that of the 50 bore 16.

The sleeve 21 is mounted for limited longitudinal movement relative to the plunger 17 by its connection with a pin 22 passing diametrically through spaced slots 23 in the wall of the portion 20 of said plunger. A spring 24 is interposed between said pin and a screw plug 25 in the upper end of the plunger to normally move said sleeve away from the shoulder or face 26 formed on the plunger, said sleeve preferably having its upper end 27 bevelled.

5 Both the plunger and the sleeve 21 with it are normally moved downwardly by a spring 28 mounted in the housing 15 between its top and the top of the plunger, this last named spring being stronger than the spring 24.

10 For varying the stroke of the plunger 17 an adjustable stop is provided therefore in the form of a screw 29 mounted in the plug 25 and locked in adjusted position by the lock nut 30.

15 It is to be noted that the housing member 15 and the upper part of the plunger 17 project up into the soap chamber, the portion of the plunger above the base 8 being surrounded with soap, and that as the operator presses up on the handle 31 of the plunger, he moves it upwardly against the 20 action of the spring 28, thus relieving the spring 24 of counterpressure and causing said spring 24 to move the sleeve 21 downwardly relative to the plunger to bring the pin 22 to the lower end of the slots 23 and thus separate the face 26 of the 25 plunger from the top 27 of the sleeve a certain distance, and thereafter a continued movement of the plunger brings these parts in the charge-receiving position shown in Fig. 2 where it will be 30 noted an annular space 32 is formed by the 35 plunger and sleeve. On a release of the plunger 17 by the operator from the loading position of Fig. 2 the spring 28 moves the plunger and sleeve downwardly together until the lower end of the sleeve 21 strikes the annulus 12 and the parts 40 have moved to the dotted line position shown in Fig. 2 at which time the bevelled top 27 of the sleeve has moved to a dispensing position, and as the soap falls from the space 32 within which it 45 has been confined during the movement of the sleeve 21 through the bore 16, it permits the plunger 17 under the action of the spring 28 to move to its final downward position shown in Fig. 1. Thus between the dotted line position of Fig. 2 and the full line position of Fig. 1 the relative movement between the plunger 17 and the sleeve 21 acts to forcibly eject soap from the space 50 32 formed between these parts. The soap thus ejected falls in the chute 10 and through the 55

openings between the arms 11 onto the hand or hands of the user.

If for any reason the device does not operate properly, the whole dispensing assembly may be removed from the receptacle 5 as a unit by unscrewing the threaded connection between the threaded opening 6 and the threaded portion 7. To facilitate removal of the unit, the base member 8 has a small opening 10' therein to receive the end of a spanner wrench so that it may be readily turned.

If too much or not enough soap is being delivered by the initial adjustment of the device, then by the removal of the unit from the receptacle and the removal of the guide member 15 and the inward or outward adjustment of the screw 29 the stroke of the plunger 17 may be changed. While the volume of the space 32 remains the same, actually in the dispensing of soap in powdered or other finely divided form the quantity of soap delivered from this space may be materially varied by adjusting the stroke of the plunger. Thus with an increase in stroke the annular cavity 32 is filled to a greater per cent of its volume during the operation of the device, and a greater amount of soap is dispensed than when the plunger is given a short stroke.

Where not otherwise specified the parts above described are made of metal or other suitable material.

I desire it to be understood that this invention is not to be limited to any particular form or arrangement of parts except in so far as such limitations are included in the claims.

What I claim as my invention is:

1. In a device of the character described, the combination of a receptacle having a dispensing opening, a cylindrical dispensing plunger movable in said dispensing opening and having a larger diameter slidably fitting said opening and a smaller diameter, a sleeve member slidably mounted on the portion of the plunger of smaller diameter and having an outer diameter to slidably fit in said opening, means for moving said plunger and sleeve together to a charge receiving position within the receptacle, said sleeve being movable relative to said plunger on the movement of said plunger and sleeve to a dispensing position.

50 2. In a device of the character described, the

combination of a receptacle having a dispensing opening, a tubular dispensing plunger movable in said dispensing opening and having a larger diameter slidably fitting said opening and a smaller diameter, a sleeve member slidably mounted on the portion of the plunger of smaller diameter and having an outer diameter to slidably fit in said opening, a lost motion connection between said sleeve and plunger, a spring acting on said connection to normally urge said sleeve outwardly to form a charge receiving space, and a stop to arrest movement of said sleeve and permit movement of said plunger relative thereto as said plunger is moved to a dispensing position.

3. In a device of the character described, the combination of a receptacle having a dispensing opening, a cylindrical plunger movable in said dispensing opening and having a larger diameter slidably fitting said opening and a smaller diameter, a sleeve member slidably mounted on the portion of the plunger of smaller diameter and having an outer diameter to slidably fit in said opening and provided with an outwardly bevelled upper end, means for moving said plunger and sleeve together to a charge receiving position within the receptacle, said sleeve being movable relative to said plunger on the movement of said plunger and sleeve to a dispensing position.

4. In a device of the character described, the combination of a receptacle having a base member provided with a dispensing opening, a reciprocating plunger working in said opening, guide means for the upper end of the plunger, spring means interposed between said plunger and guide means, an adjustable stop on the upper end of the plunger engageable with said guide means to limit the stroke of said plunger, said plunger including relatively movable parts having a lost motion connection with each other and acting to form a charge receiving space in the upper position of the plunger, spring means acting to normally move said parts to a charge receiving position on the charging movement of said plunger, said parts acting to decrease the volume of said space as the plunger moves to dispensing position.

HOWARD A. MULLETT. 50
